(57) **CLAIM**

The ornamental design for a display screen or portion thereof with graphical user interface for a video game, as shown and described.

DESCRIPTION

The patent or application file contains at least one drawing executed in color. Copies of this patent or patent application publication with color drawing(s) will be provided by the Office upon request and payment of the necessary fee.

This application is also related to U.S. Design application Ser. No. 29/800,064, filed on Jul. 19, 2021 and entitled Display Screen or Portion Thereof With Graphical User Interface for a Video Game; U.S. Design application Ser. No. 29/800,067, filed on Jul. 19, 2021 and entitled Display Screen or Portion Thereof With Graphical User Interface for a Video Game; U.S. Design application Ser. No. 29/800,070, filed on Jul. 19, 2021 and entitled Display Screen or Portion Thereof With Graphical User Interface for a Video Game; U.S. Design application Ser. No. 29/800,105, filed on Jul. 19, 2021 and entitled Display Screen or Portion Thereof With Graphical User Interface for a Video Game; and U.S. Design application Ser. No. 29/800,107, filed on Jul. 19, 2021 and entitled Display Screen or Portion Thereof With Graphical User Interface for a Video Game. The contents of these disclosures are incorporated herein by reference in their entirety.

FIG. 1 is a front view of a first embodiment of a first image of a display screen or portion thereof with graphical user interface for a video game;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof; and,

FIG. 11 is a front view of an eleventh image thereof.

(Continued)

The broken line around the outer portion of each figure showing the display screen is for environmental purposes only and forms no part of the claimed design.

Broken lines showing features of the graphical user interface, including text and icons, are provided for the purpose of illustrating portions of the article and form no part of the claimed design. For example, text shown in broken lines may be provided for illustrative purposes only to indicate that some text may be present in the specified location but that the particular text is not limited to any particular combination of alphanumeric characters.

The appearance of the graphical user interface transitions sequentially between FIGS. 1-11. The process or period in which one image transitions to another forms no part of the claimed design.
